ATTORNEY

UNITED STATES PATENT OFFICE.

EDWARD KRONMAN, OF NEW YORK, N. Y.

STERILIZING AND WATER-HEATING DEVICE.

Application filed February 6, 1925. Serial No. 7,343.

To all whom it may concern:

Be it known that I, EDWARD KRONMAN, a citizen of the United States, and a resident of the borough of Manhattan, city, county, 5 and State of New York, have invented certain new and useful Improvements in Sterilizing and Water-Heating Devices, of which the following is a specification sufficient to enable those skilled in the art to which the 10 invention appertains to utilize the same.

My improvements relate to sterilizing and water heating apparatus generally, but more particularly to the type of such apparatus designed for use in barber shops, hospitals, 15 and other places in which a continuous supply of hot water for shaving, washing, and analogous purposes is desirable, in conjunction with means for effecting the sterilizing of large quantities of towels, napkins and 20 the like for sanitary reasons, substantially as set forth in Letters Patent #1,508,187 issued to me September 9th, 1924, my present invention relating more particularly to the sterilizing hood and its connection with 25 the body or tank section of the apparatus, and consisting in the specific combination, construction and arrangement of parts and appurtenances described and claimed, whereby certain advantageous results are attained, 30 all as hereinafter set forth.

In the accompanying drawings I illustrate a practical embodiment of the essential features of my invention in conjunction with a barber's water heating and sterilizing apparatus of the character designated, although I do not limit myself to the identical construction of parts shown by way of exemplification, since changes may be made 35 in minor details, and equivalent mechanical expedients resorted to with like results, and without departing from the spirit and intent of my invention in this respect.

With this understanding:

Fig. 1, is a front elevation of such apparatus, with the sterilizing dome in closed position;

Fig. 2, is a front elevation of the upper part of the apparatus, with the dome in open position;

Fig. 3, is a section taken upon plane of line 3—3, Fig. 2;

Fig. 4, is a section taken upon plane of line 4—4, Fig. 3;

Fig. 5, is a central sectional view, upon a 55 larger scale, of the upper portion or neck

of the casing on which the sterilizing dome is rotatably mounted;

Fig. 6, is a top view of the part shown in Fig. 5;

Fig. 7, is a top view of the removable drain floor of the sterilizing hood or dome;

Fig. 8, is a section thereof taken upon plane of line 8—8, Fig. 7;

Fig. 9, is a side elevation of the dome closure member;

65

Fig. 10, is a front elevation thereof.

Fig. 11, is a view like unto Fig. 3, only upon a larger scale, and showing the hood in closed position, and indicating the presence of towels or like articles for sterilization;

Fig. 12, is a view of the underside of the hood as removed from the neck of the casing or superstructure of the apparatus.

The internal arrangement, construction 75 and operation of the apparatus A, below the neck portion A', thereof is essentially the same as described in my aforesaid Letters Patent #1,508,187, and hence need not be considered further herein except for the 80 fact that the steam for sterilization in the dome D, is derived therefrom.

The interior of said hood or dome D, constitutes the sterilizing chamber D', the dome D, being of essentially globular configuration, and being rotatably mounted on the neck A', of the apparatus, preferably on ball bearings b, b, positioned in an annular groove or raceway a, forming an integral part of the upper extremity of said neck A', 90 as shown more particularly in Fig. 5, of the drawings, by reference to which it will also be understood that said neck A', is furthermore formed with a rigid integral cylindrical sleeve a', having a concentric inner cylindrical sub-sleeve a'', the lower portions of said sleeve a', and its sub-sleeve a'', being integrally united by a connective flange a'',—

the said three parts a', a'', a'', forming a pocket a'', for the accommodation of a cylindrical sleeve d', on the base of the dome D,

as hereinafter set forth. The sub-sleeve a'', has rigidly attached to its inner surface at one side thereof the socket a'', for the reception and support of the shank s, of the stand ard s', on the upper extremity of which the stationary shutter S, is rigidly mounted.

The lower portion of the dome D, is truncated and formed with a basic annular flange d, of sufficient depth to form a hous- 110

ing for the annular rail d' , which, when the dome D, is in position on the neck, A', rests upon the aforesaid encircling series of ball rollers, b, b, thus constituting an anti-friction bearing upon which said hood or dome D, is rotatably supported, it being understood that the rail d' , is rigidly attached to the inner side of said basic flange d , and said rail d' , being formed with a pendent cylindrical flange d^2 , which fits within the pocket a^2 , between the sleeves a' and a^2 , of the neck A', hereinbefore referred to.

The sterilizing chamber D', is provided with a removable drainage floor f, formed with a pendent cylindrical extension f', which, when the floor f, is in normal position within the sterilizing chamber D', extends down into the sub-sleeve a^2 , both the floor f, and its said central cylindrical extension f', being formed with perforations f^2 , which provide for the admission of steam from the neck A', to the sterilizing chamber D',—the steam ascending through the sub-sleeve a^2 , and the cylindrical flange d^2 , on the annular rail d' , functioning as a trap or shield to exclude the steam from said anti-friction ball bearing.

The draining floor f, is formed with a recess f^2 , for the accommodation of the standard s', of the stationary shutter S, both the latter and the drain floor f, being removable upon occasion, as for purposes of cleansing, through the access aperture D $\times$, formed in the upper portion of the dome D, primarily for the purpose of affording access to the interior of the sterilizing chamber D', for the insertion or removal of clothes to be impregnated with steam in said sterilizing chamber in a manner heretofore well known in the art. Said access aperture D $\times$, being closed normally by the stationary shutter S, as indicated more particularly in Fig. 12, of the drawings, which also illustrates the function of treatment of clothes supported on the drain floor f.

The stationary shutter S, is positioned at the rear of the sterilizing chamber D, so that when the access aperture D $\times$, in the dome is closed thereby, as in Fig. 1, of the drawings, the apparatus, viewed from the front particularly, is of symmetrical appearance, the access aperture D $\times$, being at the rear end and out of sight. This is desirable from an esthetic point of view, whereas when the dome is turned with the access aperture D $\times$, to the front said aperture may be freely and conveniently used either for the insertion or removal of towels or other analogous clothes subject to treatment.

By reference, the dome is provided with an annular handle d^2 , rigidly attached to the exterior of the basic flange d , and of elliptical form in cross section, as shown more particularly in Figs. 3 and 11, of the drawings, although this is not an essential

feature of my invention, since any suitable mechanical expedients may be resorted to, to facilitate the rotation of the hood D, on the neck A'.

What I claim as my invention and desire to secure by Letters Patent, is:—

1. In water heating and sterilizing apparatus of the character designated, the combination with the neck of the steam generator, etc., of a sterilizing hood rotatably mounted on said neck and formed with an access aperture on one side thereof, a stationary shutter positioned within said hood, means for manually rotating said hood, and a perforated drain floor in said hood formed with a recess to accommodate the standard supporting said stationary shutter, substantially in the manner and for the purpose set forth.

2. In water heating and sterilizing apparatus of the character designated, the combination with the neck of the steam generator, etc., of a sterilizing hood rotatably mounted on said neck and formed with an access aperture on one side thereof, a stationary shutter positioned within said hood, and a perforated drain floor in said hood formed with a recess to accommodate the standard supporting said stationary shutter, said stationary shutter and said drain floor being insertable and removable through said access aperture in the hood, substantially in the manner and for the purpose set forth.

3. In water heating and sterilizing apparatus of the character designated, the combination with the neck of the steam generator, etc., of a sterilizing hood formed with an access aperture on one side thereof, and rotatably mounted on an annular series of anti-friction rollers positioned in a groove on said neck, said hood being formed with an annular rail resting on said rollers, and with means for manually rotating said hood and a stationary shutter positioned within said hood, substantially in the manner and for the purpose set forth.

4. In water heating and sterilizing apparatus of the character designated, the combination with the neck of the steam generator, etc., of a sterilizing hood formed with an access aperture on one side thereof, and rotatably mounted on an annular series of anti-friction rollers positioned in a groove on said neck, said neck being also formed with an internal sleeve and sub-sleeve united at the bottom to form an annular pocket, said hood being also formed with an annular rail resting on said rollers and said rail being formed with a pendent cylindrical flange fitting in said annular pocket in the neck, together with a shutter fixedly positioned in said sterilizing hood, substantially in the manner and for the purpose set forth.

5. In water heating and sterilizing apparatus of the character designated, the combination with the neck of a steam generator, of a sterilizing chamber and a hood rotatably mounted on said neck, a removable drainage floor for said sterilizing chamber provided with perforations and having a pendent cylindrical extension, an

antifriction ball bearing for said hood, the lower end of said dome having an annular flange and an annular flange rail resting upon said ball bearing and means forming a trap to exclude steam from said bearing.

EDWARD KRONMAN.
